Attorney, Agent, or Firm—Lee, Mann, Smith, McWilliams, Sweeney & Ohlson[57] **CLAIM**

The ornamental design for a seat, as shown and described.

DESCRIPTION

FIG. 1 is a perspective of a seat, showing my new design in the form of a sofa;

FIG. 2 is a left side elevational view, the right side being a mirror image thereof;

FIG. 3 is a top plan view thereof;

FIG. 4 is a front elevational view thereof;

FIG. 5 is a rear elevational view thereof;

FIG. 6 is a perspective view of a second embodiment of a seat, showing my new design in the form of a love seat;

FIG. 7 is a left side elevational view, the right side being a mirror image thereof;

FIG. 8 is a top plan view thereof;

FIG. 9 is a front elevational view thereof;

FIG. 10 is a rear elevational view thereof;

FIG. 11 is a perspective view of a third embodiment of a seat, showing my new design in the form of a chair;

FIG. 12 is a left side elevational view, the right side being a mirror image thereof;

FIG. 13 is a top plan view thereof;

FIG. 14 is a front elevational view thereof; and,

FIG. 15 is a rear elevational view thereof.
